UNITED STATES PATENT OFFICE.

HERMAN L. STRONGSON, OF BROOKLYN, NEW YORK, ASSIGNOR TO THE THOMAS & BETTS CO., OF ELIZABETH, NEW JERSEY, A CORPORATION OF NEW JERSEY.

CABLE CONNECTER.

Application filed October 18, 1923. Serial No. 669,200.

This invention relates to cable connectors and electrical fixture boxes, such as outlet boxes, switch boxes, cable boxes, connectors, and the like.

5 An object of the invention is to produce an improved combination cable connector and electric fixture box possessing structural improvements in the way of cable and conduit anchoring or fastening means; and 10 an important feature of the invention resides in the single piece structure of the connector carrying no screws or other cable clamping accessory device, and a small amount of material is used in manufacturing the connector.

An additional object is to produce an improved cable connector of simple one piece structure capable of being manufactured by stamping and drawing the connector 20 from sheet metal thereby saving casting operations. Likewise it is an object to produce a cable connector which positively functions to securely fasten an armored cable to said box as well as produce a cable connector 25 which fits standard round knock-out holes in boxes of present-day use.

The accompanying drawing illustrates a preferred form of the invention, the construction of which may be suitably varied 30 in certain respects without departing from the scope and principle of my invention.

Figure 1 illustrates a plan view of an outlet box with a cable joined thereto by the use of the improved connector; and Figure 35 2 shows a sectional view taken on the line 2-2 of Figure 1.

Figure 3 illustrates a perspective view of the cable connector.

Figure 4 shows an outside view of an assembled connector, box, and cable.

Figures 5 and 6 illustrate modified forms of the invention, the first view being in plan, while the second view shows an outside elevation of the assembled elements.

45 Referring now more particularly to the drawing first for a description of the box, there is shown a box B of conventional design having a standard round knock-out cable receiving hole H; and the box may be 50 formed with a notch 9 cut from the upper edge thereof and extending downwardly towards the said knock-out H. Thus we have a combination notch 9 and standard round knock-out hole H for use in connecting a cable to the box as will be described;

and a feature of my invention resides in the structure and arrangement of parts whereby the notch 9 is substantially closed thereby providing a sealed box structure after the said box, the cable connector, and the cable are all assembled.

55 The box is also provided with a drawn or swedged in wall 10 having an opening 11 for the reception of the legs or forked ends of a cable connector as will be described. The said swedged in wall 10 and spaced 60 openings 11 are formed in the box wall B substantially in alignment with the notch 9 and knock-out hole H, the arrangement being such that a connector cooperates with 65 the three openings made in the box wall to securely anchor a cable in the box knock-out as well as securely hold the connector 70 in the box.

Coming now to a description of the connector itself, there is shown a stamped member provided with clamp legs and having a cable stop wire bushing spaced from the legs. The stamped connector consists of a substantially U-shaped or looped body 14 one part 75 of which terminates in a bifurcated structure affording a plate made of prongs or legs 15. The adjacent internal edges 16 of the said prongs or legs extend angularly with relation to the longitudinal axis of the 80 said connector thereby converging toward the top. It is this design of the connector device which causes it to clamp upon a cable with great holding force.

85 The other side or part of the loop or U-shaped body 14 extends downwardly to an offset web or portion 17 which is turned down to form a cable bushing and wire support part 18. In this manner the body extremities or plates 15 and 18 are spaced from 90 each other a distance sufficiently far as will permit a cable extremity C to be well inserted within the box hole H thereby avoiding the possibility of attempting to secure 95 a grip on the cable end at a point too near the extremity thereof. The cable stop or bushing plate 18 is made with a drawn or swedged out bushing 19 which affords an oval edged or rounded hole surface through 100 which the cable wires W pass in making electrical connections in the box B. It is observed that the looped body 14 comprises two closely spaced walls or plates affording 105 a slide receptacle into which the wall B of the box closely fits thereby causing the body 110

- edges which converge on a cable and defining an opening over the box hole through which the cable is received through the connector into the box, said pronged portion 5 being on the outside of the box, and a bushing formed in that connector portion which is inside the box through which wires pass from the cable.
5. Cable and box connecting means comprising in combination, a box with a hole, a U-shaped connector placed astride the box wall and driven down thereon and having a cable opening registering with the box hole into which a cable is received, said connector including cable engaging prongs, and said box having an opening in the wall thereof to receive the end of each prong.
6. Cable and box connecting means comprising a box with a hole, a connector fashioned from sheet metal bent into substantially 20 U-shaped form which fits astride the box wall and is driven into position over the box hole, which provides one portion inside the box and another outside thereof, said 25 outside portion having a cable engaging and gripping opening registering with the box hole, and said inside portion including an off-set which spaces it from the box hole and including a bushing in the spaced portion.
- 30 7. A cable connector comprising, a sheet metal part bent to form closely spaced parallel portions at one end of the connector to straddle a box wall above the hole therein, and including a forked cable engaging portion with converging gripping edges which 35 bite into a cable.
8. A connector comprising, a sheet metal U-shaped part including a bifurcated cable engaging member, and including a bushing spaced therefrom in line with the bifurcation. 40
9. A connector comprising, a sheet metal member bent to bring its ends into parallel position, one end including a cable gripping opening, and the other end including a bushing in line with said opening. 45
10. A connector as defined in claim 8 wherein the end carrying the bushing has an off-set which spaces the bushing from the cable gripping opening. 50
11. A connector comprising, a sheet metal member bent to form closely spaced parallel portions, having an off-set in one portion to provide parallel portions of greater spacing than that of the first named parallel portions, a cable gripping opening in one portion, and a bushing in the other portion in line with the opening. 55
12. A connector as defined in claim 10 wherein the cable opening consists of a U-shaped forked opening with converging gripping edges. 60

In testimony whereof I affix my signature this 26th day of Sept. 1923.

HERMAN L. STRONGSON.
